UNITED STATES PATENT OFFICE.

EDWARD COPE, OF NOTTINGHAM, ENGLAND.

DESIGN FOR A LACE FABRIC.

SPECIFICATION forming part of Design No. 22,282, dated March 14, 1893.

Application filed December 19, 1892. Serial No. 455,704. Term of patent 14 years.

To all whom it may concern:

Be it known that I, EDWARD COPE, a subject of the Queen of Great Britain, residing at Chilwell Hall, Nottingham, England, have invented and produced a new and original Design for a Lace Fabric, of which the following is a specification, reference being had to the accompanying drawing, which shows a piece of lace fabric having my design.

The leading feature of my design consists of a lace fabric showing a series of parallel longitudinal bars arranged equal distances apart having looped forms projecting laterally therefrom in opposite directions. The longitudinal bars are interrupted at intervals by transverse strips wherein the looped forms disappear and the pattern is plain.

In the drawing, A indicates the parallel longitudinal bars, provided with the laterally projecting loops a' , on each side. 20

B indicates the transverse interrupting strips, wherein the pattern is plain.

I claim—

The design for a lace fabric herein shown and described.

EDWARD COPE.
